[57] CLAIM

The ornamental design for a thermal type expansion valve, as shown and described.

DESCRIPTION

FIG. 1 is a top plan view of a thermal type expansion valve;
FIG. 2 is a bottom plan view thereof;
FIG. 3 is a rear elevational view thereof;
FIG. 4 is a front elevational view thereof;
FIG. 5 is a right side view thereof, the left side view being a mirror image of the right side view;
FIG. 6 is a front perspective view thereof;
FIG. 7 is a top plan view of a second embodiment of the thermal type expansion valve;
FIG. 8 is a bottom plan view thereof;
FIG. 9 is a rear elevational view thereof;
FIG. 10 is a front perspective view thereof;
FIG. 11 is a right side view thereof, the left side view being a mirror image of the right side view;
FIG. 12 is a front perspective view thereof;
FIG. 13 is a top plan view of a third embodiment of the thermal type expansion valve;
FIG. 14 is a bottom plan view thereof;
FIG. 15 is a rear elevational view thereof;
FIG. 16 is a front elevational view thereof;
FIG. 17 is a right side view thereof, the left side view being a mirror image of the right side view;
FIG. 18 is a front perspective view thereof;
FIG. 19 is a top plan view of a fourth embodiment of the thermal type expansion valve;
FIG. 20 is a bottom plan view thereof;
FIG. 21 is a rear elevational view thereof;
FIG. 22 is a front perspective view thereof;
FIG. 23 is a right side view thereof, the left side view being a mirror image of the right side view; and,
FIG. 24 is a front perspective view thereof.
